PRODUCTION OF ARTIFICIAL FILAMENTS
AND LIKE MATERIALS

Henry Dreyfus, London, England

Application May 18, 1934, Serial No. 726,275
In Great Britain May 24, 1933

7 Claims. (Cl. 18—8)

This invention relates to the production of artificial filaments and like materials, and particularly to the production of such materials by the dry or evaporative method, according to which a spinning solution of the basic material in a suitable solvent liquid is extruded through a spinning jet into an evaporative atmosphere where the solvent is eliminated.

The usual apparatus for carrying out this process consists in a vertical spinning cell provided with heating means which bring air admitted into the cell to the required temperature, the spinning jet being arranged near the top of the cell so that the filaments or the like extruded from the jet pass downwardly to an aperture located at or near the bottom of the cell, from which aperture they are led to a winding or twisting and winding device. In a very common construction of cell the jet is carried by a candle filter arranged inside the cell, and, following the arrangement described in U. S. Patent No. 1,602,125, the hot air which ascends to the top of the cell exerts a considerable heating effect upon the spinning solution passing through the filter candle on its way to the jet.

With the continued increase in the rate of production rendered possible by improvements in the dry-spinning operation and the consequent increased rate of flow of spinning solution to the jet, a lesser degree of heating of the spinning solution takes place, and for any particular size of filter and arrangement of pipes leading the solution to the jet the temperature difference between the spinning solution when extruded and the hot air at the top of the cell becomes more marked. Even though the lower temperature of the spinning solution is not necessarily prejudicial to the actual operations of extrusion and evaporation in the cell, the spinning solution may not be heated sufficiently to bring it to the degree of fluidity which enables the filter to exert to the best effect the homogenizing action which it performs prior to extrusion in addition to its filtering function.

It is the object of the present invention to devise a filter member which will enable full use to be made of the heating capacity of the air in the cell on the spinning solution on its way to the jet so as to bring the solution into the best condition for rapid, stable spinning.

According to the invention, a filter member is provided which is removed from the neighbourhood of the jet, and is arranged so as to be reached by hotter air in the cell. At the same time the dimensions of the filter member are in-

creased to enable greater heating to be obtained, these dimensions depending for one thing upon the output of the cell measured in terms of quantity of spinning solution extruded. Such filter member may, for example, be situated relatively close to one wall of the cell so as to receive the full effect of the current of hot air proceeding upwards from the heating means which, as mentioned before, are arranged near the sides of the cell. This disposition of the filter member not only enables it to be located so as not to interfere with ordinary access to the spinning jet and to be easily reached for attention such as cleaning—a point of considerable importance—but also allows it to have such dimensions, particularly in the matter of length, as will allow adequate filtering or heat exchange surface without disturbing the position of the spinning jet, which then remains suitably near the top of the cell to allow the extruded filaments to have the maximum possible length of drying run within the cell.

If desired the filter member or filter body may be connected in series to a filter candle mounted in the usual place and serving as a jet support. When such an arrangement is employed, due regard should be paid in determining the dimensions of the filter member according to the invention or the dimensions of the filter candle, or preliminary filter body, to ensure that the combined action of the two results in bringing the spinning solution to the required state of fluidity in accordance with the particular spinning conditions prevailing. Alternatively, the filter candle may be used as or replaced by a mere heater if the filtering capacity of the filter member is adequate, such arrangement increasing the fluidity of the solution before filtration commences. Further, in some circumstances, the filter candle may be dispensed with altogether and replaced by a pipe leading the spinning solution to the filter member.

As previously stated, the filtration is affected by the quantity of spinning solution passing to the jet, and it may, moreover, be influenced by the particular characteristics of the spinning solution itself. By the use of the filter member according to the invention, solutions of higher concentration, and consequently increased viscosity, can be readily brought to a condition for ready and complete filtration. Again, the filtration is affected by the viscosity of the cellulose acetate or other cellulose derivative dissolved in the solution, particularly when the solutions are of high concentration, and again the invention

is of particular advantage in enabling solutions of such materials to be readily filtered.

A convenient form of filter member comprises a long cylindrical casing containing an internal pipe running along its length, the walls of the pipe being perforated, and covered with a filtering medium, such as a fabric of suitable weave. The solution passes into the annular space between the pipe and the casing, through the filtering medium and the perforations to the interior 10 of the pipe, and out of the pipe. It is preferable that the inner tube should only be perforated over a part of its length, so that filtration does not occur immediately upon entry of the spinning solution into the filter member. Thus, the 15 filtering material may cover approximately the half of the tube remote from entry, the tube only being perforated in this half. The tube, of course, is completely closed at its one end so that the whole of the spinning solution is forced to pass through the filtering material. If, however, the filter member is arranged so that entry of the spinning solution takes place at the opposite end to the outlet, the filtering material may be arranged over any part of the tube and may even 20 cover its whole length since any tendency to short circuiting of the spinning solution is largely avoided.

In view of the adequate heating of the spinning solution which may be obtained by the device according to the invention by suitably dimensioning the device in accordance with the characteristics of the solution and the rate of flow of the solution, it is even possible to bring the solution to a temperature higher than that immediately adjacent the nozzle, for, although the solution may have a somewhat lower temperature than the air which is used to heat it, it can be so efficiently heated that, if desired, the 30 temperature difference is less than the temperature drop of the air due to evaporation of the extruded solution.

It has already been mentioned that other cellulose derivatives than cellulose acetate may be used in the spinning solution. As examples of 40 these may be cited other cellulose esters, e. g. cellulose formate, propionate, and butyrate, and cellulose ethers, e. g. ethyl and benzyl cellulose, and particularly those of high viscosity.

By way of example the invention will now be 50 described in greater detail with reference to the accompanying drawing in which:—

Figure 1 is a sectional side elevation of a spinning apparatus fitted with filter according to the 55 present invention;

Figure 2 is a sectional plan view of Figure 1.

Figure 3 is a view on a larger scale of the filter and its connections as employed in Figure 1; and

Figure 4 is a sectional side elevation showing another method of fitting the filter.

Referring to Figures 1-3 a spinning cell 6 is fitted with a supply pipe 7 conducting spinning solution into a preliminary filtering body or filter candle 8. From the body 8 the solution proceeds through a connecting piece 9 and a pipe 10 to the filter member or filter body 11 which is disposed, as shown in Figure 2, in the corner of the spinning cell 6 and close to the heating pipes 12, banks of which are disposed at the front and back of the cell. Figure 2 also shows the cell 6 to be one of a series of cells to which the banks of pipes 12 are common, the pipes running the whole length of the series. The filtered spinning solution returns from the filter body 11 by means 70 of a pipe 13 to the connecting piece 9 and is ex-

truded through a spinning jet 14 in the form of filaments 15. The filaments are passed round a guide 16 and are led from the spinning cell 6 to a feed roller 17 conducting them to the guide 18 of a cap spinning device 19 by means of which 5 they are twisted and wound.

Figure 3 shows the filter body 11 and its connections in greater detail. The filter body consists of a long cylindrical casing 20 fitted at one end with a plug 21 into which is screwed an inner pipe 22 extending along the length of the cylindrical casing. The other end of the cylindrical casing is closed by means of a plug 23. The inner pipe is perforated over the lower half of its length at 24 so as to provide a passage between the 10 annular space between it and the cylindrical casing 20, and its interior, and filtering medium 25 is secured round the perforated part of the pipe, the dimensions of the two members and the thickness of the filtering medium being such 15 that a narrow annular passage is left for the spinning solution along the inside of the casing 20. The lower end of the tube 22 is closed by 20 means of a plug 26.

In the plug 21 a passage 27 is provided for the 25 connection of a pipe 10 by means of a suitable union 29, the pipe 10 being connected at its upper end by means of a union 30 to the connecting piece 9. The pipe 30 communicates with a passage 31 in the connecting piece 9 which passage 30 in turn communicates with the preliminary filtering body 8. A central passage 32 in the plug 21 is connected by means of a union 33 to a pipe 13 leading through a union 35 to the lower part of the connecting piece 9. The spinning jet 14 is 35 secured to the lower part of the connecting piece 9 and communicates with the pipe 13. An insulated dividing pad 36 is provided in the middle of the connecting piece 9 to prevent heat exchange between the spinning solution about to pass into the jet 14 and the spinning solution coming from the preliminary filtering body 8.

The above described arrangement constitutes a filter having a high efficiency as a heat exchanger and the advantage of the rapid heat 45 transfer rendered possible by the solution flowing as a thin stream while being heated immediately prior to filtration enables the whole device to be of relatively small size and so able to be placed where it will be surrounded only by the hottest 50 air in the cell.

The spinning solution is delivered first to the annular space between the outside casing 20 and the inner pipe 22 so that it is subjected to the heating effect of the outside air while passing 55 down the casing and before filtration takes place. Since only the lower part of the inner pipe 22 is perforated, the whole of the spinning solution must pass down the annular space and be subjected to the heating effect. In this way the solution is brought to a high degree of fluidity, with consequential advantage as regards the actual filtering. After filtration the solution passes through the inner pipe 22 and is insulated against cooling by the surrounding layer of spinning solution. The relatively low thermal conductivity of the spinning solution prevents any material change in the temperature of the solution as it passes through the inner pipe.

The filter body 11, as is previously stated, is 70 arranged in the corner of the spinning cell and is supported by the connecting pipes 10, 13. These pipes, particularly the pipe 13, may be insulated to prevent any local attemperation of the spinning solution therein. Furthermore, the interior 75

of the filter body is readily accessible, and by removing the plugs 21 and 23 at each end of the outer casing 20, all parts of the filter can be easily and completely cleaned. By reason of the provision of the unions 29, 30, 33, 35, the filter body with or without the connecting pipes 10, 13 can readily be removed for cleaning purposes and for the changing of filtering material.

The arrangement described above includes a preliminary filtering body 8. The provision of such a body enables a slightly smaller filter body 11 to be employed, but if desired, the filter body 8 may merely serve the purpose of, or may be replaced by, a heat exchanger for a preliminary heating of the spinning solution.

An alternative arrangement is shown in Figure 4, in which the body 8 is dispensed with altogether and the supply pipe 7 leads through the top of the cell 6 directly into the connecting piece 9 to which the pipes 10, 13 are connected. The filter body 11 is supported by the pipes 10, 13, directly over the heating pipes 12 from which a current of hot air ascends to surround the filter body.

25 What I claim and desire to secure by Letters Patent is:—

1. Apparatus for the production of extruded artificial materials by the evaporative method comprising a spinning chamber, means in said chamber for heating evaporative medium in said chamber, a spinning jet for the extrusion of a spinning solution into such evaporative medium, and a filter member connected in series before said jet, and disposed in a position removed from the neighbourhood of said jet, and in the neighbourhood of said heating means.

2. Apparatus for the production of extruded artificial materials by the evaporative method comprising a spinning jet for the extrusion of a spinning solution into an evaporative medium, a preliminary filter body disposed above said jet and a main filter member connected in series between such preliminary filter and said jet, and disposed in a position removed from the neighbourhood of said jet.

3. Apparatus for the production of extruded artificial materials by the evaporative method comprising a spinning chamber, means in said chamber for heating evaporative medium in said chamber, a spinning jet for the extrusion of a spinning solution into such evaporative medium, a preliminary heating member disposed in the top of said spinning chamber for heating such spinning solution, and a filter member connected in series between said heating member and said jet, and disposed in a position removed from the neighbourhood of said jet, and in the neighbourhood of said heating means.

4. Apparatus for the production of extruded artificial materials by the evaporative method, comprising a spinning chamber, means in said chamber for heating evaporative medium in said chamber, a spinning jet for the extrusion of a spinning solution into such evaporative medium, and a filter member connected in series before

said jet and disposed in a position removed from the neighbourhood of said jet and in the neighbourhood of said heating means, said filter member comprising an outer cylindrical casing, a perforated inner tube covered with a filtering medium, an inlet connection for leading the spinning solution to the inside of said outer cylindrical casing, and an outlet connection for leading the spinning solution away from the inside of said inner tube.

5. Apparatus for the production of extruded artificial materials by the evaporative method, comprising a spinning chamber, means in said chamber for heating evaporative medium in said chamber, a spinning jet for the extrusion of a spinning solution into such evaporative medium, and a filter member connected in series before said jet and disposed in a position removed from the neighbourhood of said jet and in the neighbourhood of said heating means, said filter means comprising an outer cylindrical casing, an inner tube, an inlet connection for leading the spinning solution to the inside of said outer cylindrical casing, and an outlet connection for leading the spinning solution away from the inside of said inner tube, said inner tube being perforated over a part of its length remote from said inlet connection and covered over its perforated part with a filtering medium.

6. Apparatus according to claim 5, wherein the outlet connection is formed at the end of the inner tube remote from the perforated portion of the tube so that the solution on entering the filter through the inlet connection is caused to traverse the length of the outer casing before reaching the perforated portion of the inner tube, and then to traverse the length of the inner tube before leaving the filter through said outlet connection.

7. Apparatus for the production of extruded artificial materials by the evaporative method, comprising a spinning chamber, means in said chamber for heating evaporative medium in said chamber, a spinning jet for the extrusion of a spinning solution into such evaporative medium, and a filter member connected in series before said jet and disposed in a position removed from the neighbourhood of said jet and in the neighbourhood of said heating means, said filter member comprising an outer cylindrical casing, a perforated inner tube disposed within said casing in such a manner as to leave an annular space between the outer casing and the inner tube, said tube being covered with a filtering medium, a removable plug closing one end of said outer cylindrical casing, a removable plug closing the corresponding end of the perforated inner tube, and a further removable plug disposed at the other end of the filter, said further plug closing the other ends of both the outer cylindrical casing and the inner tube while allowing of the passage of spinning solution into the annular space between the outer casing and the inner tube, and out of the inner tube.
